Primary Examiner—Jeffrey Asch*Assistant Examiner*—Carla Jobe Wright(74) *Attorney, Agent, or Firm*—Birch, Stewart, Kolasch & Birch, LLP(57) **CLAIM**

The ornamental design for a portable terminal, as shown and described.

DESCRIPTION

FIG. 1 is a front, left perspective view of the portable terminal showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view showing a sliding state of the display part of the present design; and,

FIG. 9 is a left side showing a sliding state of the display part of the present design.
